UNITED STATES PATENT OFFICE.

GEORGE C. JENSEN, OF OAKLAND, CALIFORNIA.

LOCKING DEVICE FOR LEVERS.

1,253,384.

Specification of Letters Patent. Patented Jan. 15, 1913.

Application filed September 27, 1917. Serial No. 193,405.

To all whom it may concern:

Be it known that I, GEORGE C. JENSEN, a citizen of the United States, residing at Oakland, in the county of Alameda and State of California, have invented certain new and useful Improvements in Locking Devices for Levers, of which the following is a specification.

The present invention relates to locking devices for levers, particularly designed for use in connection with the variable speed power transmitting mechanism of a motor vehicle, and has for its principal objects to provide a simple and efficient locking means for levers of the described type, which is capable of being constructed at little cost and one consisting of but few parts.

The invention consists broadly in a bolt or member connected to the lever and slidably mounted in a guide and coöperating with which is a locking member for engaging the same to prevent lineal movement of the bolt within its guide and thus lock the lever from operative movement.

To more fully comprehend the invention, reference is directed to the accompanying drawings, wherein—

Figure 1 is a vertical sectional view of the preferred embodiment of my invention.

Fig. 2 is a transverse sectional view taken on line 2—2 of Fig. 1.

Referring more particularly to the several views of the drawings, wherein like characters of reference designate corresponding parts, 1 indicates a suitable housing formed in its top wall 2 with a vertical opening 3, through which extends the lever 4. The lever is formed intermediate of its length with a spherical portion 5 for seating in a spherical socket 6 formed in the inner wall surface of the opening 3, thus providing a socket for the lever, wherein the same is capable of universal swinging movement.

A suitable ring 7 is adapted to retain the lever in its socket 6 in the housing.

Pivottally connected, as at 7', to that portion of the lever 4 within the housing 1, is a bolt 8 adapted to lie at right angles to the lever and arranged in parallel spaced relation to the underside of the top wall 2 of the housing 1. The bolt is received at its free end within a suitable pocket or recess 9 formed in the housing 1, which provides a guide therefor. A suitable enlarged bearing surface 10 is formed annularly of that portion of the bolt within the recess 9 and the

same contacts with the walls of said pocket, providing a sliding fit for the bolt when moved longitudinally and oscillated therein during the movement of the lever. The free end of said bolt 8 is provided with a vertically disposed transversely extending slot 11, the inner walls of which are formed with oppositely disposed semi-circular recesses 12 to receive the walls of a cylindrical locking tumbler 13 extending perpendicular through the recess 9 and bearing at its lower end, as at 14, in a socket 15.

The tumbler is provided on its opposite sides with flat faces 15' providing a portion thereof of a width slightly less than that of the slot 11, thus permitting lineal movement of the locking bolt on the alining of the flat faces 15' with the side walls of the slot 11. The tumbler 13 depends from the underside 75 of a cup 16 rotatably mounted in a seat 17 in the housing top wall 2 and within a seat 17' in said cup is positioned a lock casing 18, carrying a rotatable key controlled barrel 19, a portion 19' of which is disposed eccentrically thereof and projects below the same and into the transverse bore 20 formed in the cup 16.

Mounted in the bore 20 and slideable transversely of the cup is a locking pin 21 having 85 a recess 22 in its upper surface into which projects the eccentric portion 19' of the barrel 19.

A spring 23 positioned in a suitable chamber in the cup 16 bears against a lug 24 90 on the underside of the pin 21 and forces the same outwardly against the action of the eccentric portion 19' of the barrel 19.

When the parts are positioned as in the drawing, with the locking pawl precluding 95 longitudinal movement of the locking bolt and operative movement of the lever, the end of the locking pin 21 is received in a depression 24' in the side wall of the seat 17, and is removed therefrom by a slight rotation of 100 the key operated barrel 19, which causes the eccentric portion 19' thereof to move the locking pin 21 lineally until the rear end thereof contacts with the wall of said seat 17, at which time further rotation of the 105 barrel causes a rotation of the cup 16 and tumbler 13 until such time as the flat faces 15' of the tumbler aline with the faces of the slot 11, releasing the locking bolt to permit operation of the lever. The rotation 110 of the cup and barrel to lock the lever from movement is preferably accomplished

through pressure applied to the arm 25 which rotates the cup and barrel as a unit until such time as the locking pin 21 is received in the depression 24'.

- 5 It will thus be apparent that the insertion of the controlling key in the locking barrel is not required to lock the lever from movement, as the pressure on the arm 25 will cause a rotation of the barrel and cup. However, a key is required when it is desired to unlock the bolt and provide operative movement of said lever.

Having thus described my invention, what I claim as new and desire to protect by Letters Patent is:—

1. The combination with a lever, a support within which the same is fulcrumed for universal swinging movement, said support inclosing a portion of said lever, a locking bolt inclosed within said support and disposed at an angle to said lever and pivotally connected at one end to the same, a guide within the support for receiving the other end of said locking bolt and within which said bolt is capable of oscillating and longitudinal movement on the movement of the lever in its various planes, and a lock controlled locking tumbler carried by the support and extending into said guide and adapted for movement to engage said bolt to prevent longitudinal movement of the same within the guide.

2. The combination with a lever, a support within which the same is fulcrumed for universal swinging movement, said support inclosing a portion of said lever, a locking bolt concealed within said support and pivotally connected at one end to the inclosed portion of said lever, the other end of said bolt provided with an open ended longitudinally disposed slot, a guide for receiving the slotted end of said locking bolt, and a rotatably mounted lock controlled locking tumbler extending into said guide and into the slot in the end of said bolt and capable of rotation into engagement with said bolt to lock the same from longitudinal movement within said guide.

3. The combination with a lever, a sup-

port within which the same is fulcrumed for universal swinging movement, said support inclosing a portion of said lever, a locking bolt pivotally connected at one end to the inclosed portion of said lever, a guide within said support for receiving the free end of said bolt and within which said bolt is capable of longitudinal and swinging movement during the movement of the lever in its various planes, and lock controlled devices for engaging said bolt for locking the same from movement relative to said guide.

4. The combination with a lever, a support within which the same is fulcrumed for universal swinging movement, said support inclosing a portion of said lever, a locking bolt slotted at one end and pivotally connected at its opposite end to said lever, a guide for receiving the slotted end of said locking bolt, an axially rotatable locking tumbler disposed parallel with the lever extending through said guide and into said slot and capable of rotation to engage the side walls thereof, to lock said bolt from movement, and lock controlled means carried by said support for preventing the rotation of said tumbler.

5. The combination with a lever, a support for housing a portion of the same and providing a fulcrum therefor, a locking bolt arranged within said housing at right angles to the lever and slotted at one end and pivotally connected at its opposite end to the lever, a guide within the housing for receiving the slotted end of said locking bolt, a rotatable locking tumbler arranged at right angles to said locking bolt and parallel with said lever and extending into the slot thereof, said tumbler capable of rotation to engage the side walls of said slot to lock said bolt from movement, and lock controlled means for preventing the rotation of the tumbler.

In testimony whereof I have signed my name to this specification in the presence of the subscribing witness.

GEORGE C. JENSEN.
